STOVE TOP ASSEMBLY

James M. Cook and Shirly C. Salter, Kalamazoo,
Mich., assignors to Kalamazoo Stove and Fur-
nace Company, Kalamazoo, Mich.

Original application April 5, 1945, Serial No.
586,702. Divided and this application June 4,
1946, Serial No. 674,283

9 Claims. (Cl. 126—214)

1

This invention relates to improvements in stove top assembly.

This application is a division of our co-pending application for Letters Patent, Serial No. 586,702, filed April 5, 1945, issued October 18, 1949, No. 2,485,359.

The principal objects of this invention are:

First, to provide a top for a cook stove of a one-piece seamless character which will be more attractive and easier to keep clean than tops known heretofore.

Second, to provide a top assembly for a stove which may be attached by an unskilled workman, with two concealed bolts.

Third, to provide a top for a cook stove which permits easy access to the burner adjustment and connections positioned below the top.

Objects relating to the economies and details of the construction of the top will be apparent from a consideration of the following description. The drawings, of which there are two sheets illustrate a preferred form and one modified form of the invention.

Fig. 1 represents a plan view partially broken away of the top as installed on a cook stove.

Fig. 2 represents an end elevational view of the top in partially assembled position on the stove.

Fig. 3 represents a front elevational view of the front frame member of the stove which supports the top member.

Fig. 4 represents an enlarged perspective view of the stove frame structure at the rear corner thereof arranged to cooperate with the top.

Fig. 5 represents a vertical cross sectional view taken along the line 5—5 of Fig. 1.

Fig. 6 represents a vertical cross sectional view taken along the line 6—6 in Fig. 1.

Fig. 7 represents an end elevational view of a modified form of stove top.

Fig. 8 represents a plan view of the top illustrated in Fig. 7.

In the drawings the reference character 1 indicates a stove top consisting of a top panel 2, a depending forward apron 3, and a raised rear fence 4. The top panel, front apron, and rear fence are formed with a continuous surface as one stamping and are provided with merging end flanges 5 and a top flange 6 along the top of the fence 4. A vent outlet 7 is formed in the top flange 6. The top panel 2 defines a series of burner apertures 8 which are disposed over the burner elements at 9 and arranged to receive burner bowls 10 supported upon the raised bosses 11. The forward burner openings 8 are formed with extensions 12 on their forward sides so that

2

when the burner bowls are removed, the mixing valves 13 for the burners are readily accessible. The rear burner openings are formed with extensions 14 on the rear sides thereof so that access may be had therethrough to the connection 15 between the fuel manifold 16 and fuel supply pipe.

The end flanges 5 on the top panel are provided with inwardly turned flanges 18 (see Fig. 5) and the front apron portion 3 is provided with a backwardly turned flange 19 (see Fig. 6) so that the top may be attached to the body of the stove in a manner to be described presently.

The stove body to which the top is arranged to be attached includes the front frame member 15 20, rear panel 21, and top cross members 22. The front frame member 20 is formed as a unitary stamping with end vertical members 23, a center vertical member 24 and a horizontal top portion 25 defining a large horizontal slot 26 and two smaller slots 27 therebelow. The large slot 26 is provided with forwardly extending flanges 28 at the top and bottom thereof and the top of the horizontal portion is formed with three upstanding ears 29 and two sloping portions 30 defining bolt holes 31. The top cross members 22 are flanged inwardly as at 32 along the top edge thereof and are welded at their forward ends to the end uprights 23 of the front frame member and at the rear to the forwardly extending flange 33 of the rear panel 21. It will be noted that the cross members 22 extend backwardly beyond the rear panel. The rear panel is formed with upstanding ends 34 at each end thereof arranged to be welded to the inturned flange 32 on the top cross members.

A burner chamber bottom panel 35 is provided with an upturned flange 36 on the back edge which is welded to the back panel 21 and a downwardly offset edge 37 along its forward edge which is welded to the back of the front frame member.

Burner support bars 38 have their forward ends supported on the top of the lower flange 28 of the front frame member and their rear ends supported on the burner chamber bottom panel near the rear panel 21. Burners 39 are supported on the burner support members underneath the openings 8 in the top panel and are provided with mixing valves 13 positioned underneath the forward extensions 12 in the forward burner openings. The fuel manifold 16 is bent from the back of the burner chamber and extends along the front of the stove and within the horizontal slot 26 in the front frame chamber. Bolts 40 secure the manifold to the sloping portions 30 of the front frame member. Fuel valves 41 are

connected to the manifold for delivering fuel to the mixing chambers 40 and control shafts 42 project forward therefrom for connection with control knobs 43 on the forward apron section of the top member.

Secured to the inturned flange 32 of the end cross members is a spring clip 44 which is provided with a central portion 45 which extends across the forwardly turned flange 34 on the rear panel. Each end of the center portion 45 defines an aperture 46 and is turned downwardly into a lower flange 47. The lower flanges 47 are welded to the top flange on the end cross member by means of welding electrodes which are passed through apertures in the center portion 45. The end flanges 47 are further bent upwardly into the end clips 48 which are spaced upwardly at a higher level than the center portion 45 of the clip.

The center portion 45 of the clip is spaced above the top of the cross member 22 and arranged to receive the inturned flange 49 of an outer decorative end panel 50 while the end portions 48 of the clip are spaced so as to receive the inturned flange 18 of the top member between themselves and the center portion 45. The clips 44 thus slidably secure the top member to the body of the stove. The inturned flange 19 along the bottom of the apron portion 3 is arranged to fit underneath the lower flange 28 of the horizontal opening in the front frame member. Two bolts 51 are provided for securing the flange 19 to the flange 28, thus effectively securing the top member to the stove while at the same time leaving the top member readily demountable for separate packing and shipment or repair of the stove. Doors 52 are provided for the openings in the front of the stove which effectively conceal the bolts 51 when the doors are in their normally closed position.

In the modified form of the invention illustrated in Figs. 7 and 8 the end flange 54 of the top portion is extended to the same width as the depending apron portion 55 at the front of the top member. In employing this form of the invention the cross members 22 and the clips 44 on the stove frame will be correspondingly lowered.

The top portion 56 is altered in that the burner apertures 57 are positioned in pairs at each end of the stove rather than in a group of 4 as in the preferred form of the invention.

The invention has been illustrated and described in a highly practical commercial embodiment thereof. No other adaptation has been shown as it is believed that this disclosure will enable those skilled in the art to adapt the invention as may be desired.

We claim:

1. A stove or range comprising a frame unit having inturned flanges at the top of the ends thereof, outwardly facing multi-leaved clips having lower leaves secured to the under sides of said flanges near the back of said stove, end walls having inturned flanges at the upper edges thereof engaged between said flanges on said frame and intermediate leaves of said clips, and an integral top unit comprising a top surface portion, depending front and end portions of substantial width and a rear fence portion of substantial width, said depending portions being provided with inturned flanges, the inturned flanges of said end portions being engaged between said intermediate leaves and top leaves of said clips, said inturned flange on said front portion being secured to said frame by concealed fastenings.

2. A stove or range comprising end walls hav-

ing inturned flanges at the top thereof, a top having downturned end portions with inturned flanges at the lower edge thereof disposed in opposed relation to the flanges at the top of said end walls, and coupling members of multi-channel section telescopingly embracing said flanges on said end walls and said top, said coupling members having intermediate portions engaging the upper sides of said end wall flanges and the under sides of the top flanges, said intermediate portions defining apertures through which a welding tool may be passed to weld the bottom of said coupling members to the frame of said range.

3. A stove or range comprising end walls having inturned flanges at the top thereof, a top having downturned end members with inturned flanges at the lower edge thereof disposed in opposed relation to the flanges at the top of said end walls, and multi-leaved coupling members forming parallel channels telescopingly embracing said flanges on said end walls and said top with intermediate leaves of said coupling members located between said inturned flanges.

4. A stove or range comprising end walls having inturned flanges at the top thereof, a top having an integral depending front portion and end portions having inwardly projecting flanges and an integral upstanding fence member at its rear edge, and multi-leaved coupling members forming vertically spaced channel sections adapted to slidably receive said flanges on said end walls and on said end portions with intermediate leaves of said coupling members positioned between said flanges, said intermediate leaves defining openings through which a welding tool may be passed to weld the lower leaves of said coupling members to frame members of said stove, the top leaves of said coupling members being divided and located longitudinally at each end of said intermediate leaves.

5. In combination with a stove body having a front frame member with a horizontal flange extending outwardly therefrom, and an inwardly flanged end frame member, a top member formed as an integral stamping comprising a front apron portion of substantial width, a top portion, a rear fence portion of substantial height, merging end flanges formed on said apron, top, and fence portions, horizontal flanges turned inwardly from said end flange on said top portion, and a flange directed inwardly from said apron portion, said last mentioned flange being removably secured to said horizontal flange on said front frame portion and an outwardly opening U-shaped clip secured to said end frame member and engaging said inturned flange on the end of said top member, said clip having outwardly extending lower intermediate and upper leaves, said upper leaf being divided and located longitudinally of said clip at each end of said intermediate leaf, said inturned flange on said top portion being positioned between said upper and intermediate leaves.

6. In combination with a stove having end frame members with inturned flanges on the tops thereof, a top member having inturned flanges on the ends thereof, decorative end panels having inturned flanges on the tops thereof, integral U-shaped spring clips having bottom leaves welded to said flanges on said end members, second upwardly spaced leaves on said clips for engaging said flanges on said end panels against said flanges on said end frame members, and third upwardly spaced leaves spaced higher than said

second leaves for engaging said flanges on said top member against said second leaves.

7. In combination with a stove having end frame members with inturned flanges on the tops thereof, a top member having inturned flanges on the ends thereof, decorative end panels having inturned flanges on the tops thereof, integral U-shaped spring clips for joining said members and panels comprising bottom leaves welded to said flanges on said end frame members, second upwardly spaced leaves on said clips for engaging said flanges on said end panels between said second leaves and said flanges on said end frame members, third upwardly spaced leaves spaced higher than said second leaves for engaging said flanges on said top member between said second and third leaves, said second leaves defining apertures whereby a welding tool may be applied to said bottom leaves and said flanges on said end members.

8. A clip for securing the inturned flanges on a top and end panel of a stove to an inturned flange on the end frame member of a stove comprising, a stamping having lower, intermediate and upper outwardly turned leaves connected by a web portion, said leaves being spaced vertically with respect to each other, said intermediate leaf defining apertures through which a welding tool may be passed to weld the lower leaf of said clip to the bottom of said flange on said end frame member, said upper leaf being divided and located longitudinally at each end of said intermediate leaf.

9. A clip for securing the inturned flanges on

a top and end panel of a stove to an inturned flange on the end frame member of a stove comprising, a stamping having lower, intermediate and upper outwardly turned leaves connected by a web portion, said leaves being spaced vertically with respect to each other, one of the upper of said leaves defining apertures through which a welding tool may be passed to weld the lower leaf of said clip to said flange on said end frame member, one of the upper of said leaves being divided and located longitudinally at each end of the other of the upper two of said leaves.
